UNITED STATES PATENT OFFICE.

MARTIN V. B. ETHRIDGE, OF BOSTON, ASSIGNOR OF ONE-HALF TO HENRY E. WAITE, OF NEWTON, MASSACHUSETTS.

MAIL-BAG FASTENING.

SPECIFICATION forming part of Letters Patent No. 297,245, dated April 22, 1884.

Application filed March 10, 1884. (No model.)

To all whom it may concern:

Be it known that I, MARTIN V. B. ETHRIDGE, a citizen of the United States, residing at Boston, in the county of Suffolk and State of Massachusetts, have invented certain new and useful Improvements in Mail-Bag Fastenings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to that class of mail-bag fastenings or devices for securing the mouth of a bag, satchel, or similar article, in which the mouth of said article is secured by means of interlocking flanged plates attached, respectively, to the mouth of the bag and to the under side of a clasp or locking-bar; and the invention consists in the combination, with such bag and clasp, of a hasp having a lug for entering a slot in the clasp; and, further, in certain peculiarities in the construction, arrangement, and combination of parts, as hereinafter more fully described and claimed.

In the annexed drawings illustrating the invention, Figure 1 is a partial side view of the upper part of a mail-bag, satchel, or similar article provided with my improved fastening. Fig. 2 is a partial top or plan view of the mouth of the bag, showing the same closed but unfastened, the binder or flexible fastening-bar being removed. Fig. 3 is a perspective view of a portion of the flexible binder with a part of its covering or hood removed. Fig. 4 represents an end view of the binder, and also a cross-sectional view of the bag with its locking-flanges or guideways. Fig. 5 is a vertical section on the line $x-x$ of Fig. 1. Fig. 6 is a side view of one of the locking-flanges or guideways that are attached to the mouth of the bag. Fig. 7 is a sectional view of one of said guideways, showing a modification in its form.

In the mouth of the bag A, on opposite sides, are secured leather strips $a-a$, that afford a firm bearing or attachment for the locking-flanges

or guideways B B, a series of which are arranged on each side, as shown in Fig. 2. These locking-flanges are preferably made of light spring tempered steel, and each consists of a shank portion, b , that is riveted or otherwise secured to the leather strips a , and a lip portion, c , that engages with corresponding flanges on the sliding binder C, by which the mouth of the bag is secured. The metallic flanges or guideways B B are attached to the mouth of the bag in such a manner that the opposite sets correspond in position, as shown in Fig. 2, when the bag is closed, and sufficient spaces are left between the adjacent flanges or plates B on each side to enable the mouth of the bag to be opened in the form of a circle, or approximately so, when the bag is unfastened. It will be understood that the strips a are not formed in continuous pieces to extend entirely around the bag, but each of these strips is cut at the ends of the mouth, so that when the bag is closed the flanges or guideways B B, on opposite sides, will register, as shown in Fig. 2.

The flexible binder C consists of several parallel strips of leather or other pliable material, between which strips are secured a series of metallic locking-flanges, D, for engaging with and inclosing the flange B in the mouth of the bag. The flanged plates D are provided with inwardly-bent lips d , so as to interlock with the outwardly-bent lips c of the flanges or plates B, when the binder C is slid into place over the closed mouth of the bag.

It will be observed by reference to Fig. 1 that the flanged plates or locking-ways B D are arranged in such a manner as to break joints with each other, as shown in dotted lines when in position for fastening the bag, each plate D clasping two of the plates B B, thereby affording a firm and secure fastening. In order to enable the flanged plates B D to slip past each other readily in opening and closing the bag, the lips $c-d$ are made with rounded or beveled ends. By this construction, also, the ends of the lips c and d are not so liable to become jammed or bent out of shape under hard usage as would be the case if they were square-cornered. The lips c of

the flanged plates B, besides being rounded or beveled at their ends, are also preferably provided with longitudinal swells or corrugations e, having beveled ends, as shown in Fig. 5. In making these flanged plates, the steel of which they are formed is struck up into either of the forms shown by sectional views in Figs. 4 or 7, the corrugations or swells e being either in the center or on one side of the lip e. This swell or corrugation e is greatest in the middle, and tapers or diminishes gradually at the ends.

It will be seen that by forming the lips e with swells e having rounded or beveled ends, as shown, the engagement of the flanged plates B and D is greatly facilitated, and the several sections are enabled to slip readily past each other in fastening and unfastening the bag.

It will also be observed that the flexible character of the binder C enables its attached plates D to be readily slipped into engagement with the locking-ways B, the mouth of the bag being first closed, so as to bring the opposite sets of flanged plates B together.

25 The binder C is provided with a hood or covering, f, of leather or other suitable material, that extends down on each side, so as to cover the sides of the locking-plates D, as shown in Figs. 4 and 5. The mouth of the bag A is extended above the strips a a, and forms a similar covering for the locking-ways B, as shown in Fig. 5. When the binder C is in position, the locking-plates B and D are thus completely concealed and protected from 35 injury by the overlapping parts. After the binder C has been slipped into place, it is secured by means of a combined hasp and tag-holder, E, that is pivoted to the side of the bag. This hasp is provided with a slot, g, that 40 engages with a staple, h, on the side of the bag, and it also has a lug, F, that enters a slot, i, in the side of the binder C, thereby holding the binder firmly, the parts being secured by a padlock passed through the staple h over 45 the hasp, as shown in Fig. 5 by dotted lines.

The hasp and tag-holder are preferably combined in one piece, as shown, though, if desired, they may be made separate. When arranged as shown in Fig. 1, it will be seen that 50 the tag or destination-card is prevented from slipping out of its holder by the staple h until the bag has been unlocked.

By forming the flanged locking-plates of very thin steel the requisite lightness and elasticity are obtained without impairing the strength or durability of the parts. The form that is given to the flanged plates B, especially the relative curves of the lip e and its swell e, as shown, is of value in enabling the plates B and D to slip past each other without obstruction, and when these flanged plates are attached to a bearing composed of several strips of leather, a a, whereby the necessary stability is secured, and the whole series clasped by the flanged plates or locking-ways on the flexible binder, a very secure fastening is afforded.

Having thus described my invention, what I claim as new, and desire to secure by Letters Patent, is—

1. The combination, with the bag A and binder C, having slot i, of the hasp E, provided with a lug, F, for entering said slot, and means for securing the hasp, substantially as described.

2. The combination, with the bag A, having strips a a within its mouth, and flanged locking-ways B B, attached thereto, the mouth of the bag being extended above said strips to cover the sides of the locking-ways, of a flexible binder, C, having hood f and locking-ways D D, substantially as described.

3. The combination, with the bag A, having strips a a, secured within its mouth, of the flanged locking-ways B B, supported by said strips and provided with lips e e and swells e e, and the flexible binder C, having locking-ways D D, substantially as described.

4. The combination, with a mail-bag having flanged locking ways or plates B B and staple h, and a binder, C, provided with flanged locking-plates D D and slot i, of the hasp and tag-holder E, having slot g and lug F, and means for securing the hasp, substantially as described.

In testimony whereof I affix my signature in presence of two witnesses.

MARTIN V. B. ETHEridge.
